UNITED STATES PATENT OFFICE.

HUGH T. DUNN, OF NEW YORK, N. Y., ASSIGNOR OF ONE-HALF TO BENJAMIN A. JACKSON,
OF NEW YORK, N. Y.

AIR AND GAS ENGINE.

No. 903,689.

Specification of Letters Patent.

Patented Nov. 10, 1908.

Original application filed January 22, 1902, Serial No. 90,851. Divided and this application filed April 28, 1903.
Serial No. 154,677.

To all whom it may concern:

Be it known that I, HUGH T. DUNN, a citizen of the United States, and a resident of New York, in the county of New York and State of New York, have invented a new and useful Improvement in Air and Gas Engines, of which the following is a specification.

My invention relates to an improvement in explosive engines and is designed to be used in connection with the motors set forth in my co-pending application, Serial No. 90,851, filed January 22, 1902, of which this invention is a divisional part.

The object of my invention is to provide a device of the character set forth which is operated by the motor shaft and in which the explosion occurs, the effects or force thereof being conveyed directly to the inlet ports of the motor.

To this end my invention consists of an explosive or combustion chamber and means for charging the explosion chamber.

In addition to this, my invention comprises a novel means for storing a portion of the explosive charge, means for exploding the charge and many other details of construction and combinations of parts such as will be brought out more fully hereinafter and particularly pointed out in the claims.

In the accompanying drawings, Figure 1 is a view in side elevation of my improved combustion chamber and its connected parts, Fig. 2 is a view in side elevation partly in section of the explosive chamber, Fig. 3 is a view in side elevation.

A, indicates the main or line shaft which is to be rotated by the motor or motors (not shown), the shaft passing through the compressor B which is operated thereby, the compressor being constructed similarly to the motors set forth in the original application above referred to and hence, it is unnecessary to set forth its structure in detail herein; the function of the device being to create a vacuum on the inlet side of the casing which will draw thereinto a charge of air and hydrocarbon or other explosive medium which is forced out of the outlet side of the casing and conveyed to the combustion chamber C.

The main shaft A, passes through the compressor and projects out through the wall of the air tight chamber D, in which the entire mechanism is inclosed.

Leading into the air tight chamber D, from any suitable source is the main air pipe 70, which pipe is provided with branches 71, 71 leading to the two inlet ports 36, 36 of the compressor B, and situated at the junction of the branch pipes 71, 71 with the main pipe 70 is a three-way valve 73, the valve stem of which extends outside the chamber and is connected by means of a link 68 with a universal lever 69.

Outside the casing or chamber D, is a second pipe 74 designed to convey the gas, hydrocarbon or other explosive agent from any suitable source to the air pipe 70 with which it is joined by means of connection 75. Thus it will be seen that commingled air and hydrocarbon are permitted to enter the compressor B, through the inlet ports 36. A regulating or cut-off valve 76 of any suitable construction is located in the conveying pipe 74. This valve is provided with an arm 77 secured to the stem thereof.

An eccentric 78 keyed on the main drive shaft A, is connected with the arm 77 by means of the eccentric rod 79. As the shaft 80 rotates, the valve 76 will first be opened and then closed to first admit and then cut off the supply of hydrocarbon, gas or other explosive medium from the compressor B.

A governor valve 80 is placed on pipe 70 just outside of chamber D, and between the connection 75 and the three-way valve 73.

A wheel 81, is keyed on the main shaft A and a belt or chain 81' connects the wheel 81 and the governor valve 80 whereby, when the shaft A is rotating too rapidly, to operate the governor valve 80 to close the pipe 70 and restrict the amount of the charge entering the air and gas compressor B. The apertures through which the main shaft A and the pipe 70 protrude, are suitably packed.

The commingled air and hydrocarbon is drawn by suction into the compressor B, wherein it is further commingled and compressed, issuing from one or the other of exhaust ports 37, 37 to branch pipes 82, 82 as the case may be.

A three-way valve 84 similar to valve 73 is located at the meeting point of branch pipes 82, 82 and permits the compressed commingled air and hydrocarbon to issue from either branch pipe into main pipe 85. A check valve 86 is located in this main pipe to prevent the return of the compressed air and hydrocarbon. Also a branch pipe 87 is 110

connected with main pipe 85, the branch pipe having a check valve 88 located therein. The branch pipe 87 leads to a storage tank 89 supported from the ceiling of the chamber D, and as the compressed air and hydrocarbon passes through the main pipe 85, the force thereof will open the check valve 88 and permit the passage of the explosive mixture up branch pipe 87 to the storage tank 89 where 10 it is kept under pressure until required to start the explosive engine, as will be described shortly. Of course, as soon as the pressure of the compressed air and hydrocarbon in the tank 89 equals that of the 15 compressed air and hydrocarbon passing through the main pipe, the check valve will be closed and no more can pass into the storage tank on account of the pressure exerted on the check valve 88 by that already in the 20 tank. The remaining portion of compressed air and hydrocarbon passes on to the explosive engine C, through an aperture 90, protected by the check valve 90'. This engine is strongly built and consists of a chamber C 25 into which extend insulated electrodes 92, 92 suitably connected by means of insulated wires 93, 93 to batteries or other suitable source of electrical energy, not shown. These wires pass out of the chamber C, through 30 binding posts 94, 94 and to these binding posts are connected the wires leading to the battery or other source.

An eccentric 95 is fastened on the main shaft A, and is provided with the usual 35 strap 96, to which is connected an arm 98, by means of a pin 97. This arm 98 projects through a suitably packed aperture 99 into the explosive chamber C. The inner end of the arm is hollow and is provided with slots 40 100 to receive studs 101 projecting from the stem 102 of a head 103. This head is normally forced outward by means of a spring 104 seated in the hollow rod. This head 103 is located directly beneath the two electrodes 45 92, 92 and as the eccentric 95 revolves, the head 103 is forced alternately between and withdrawn from contact with the electrodes whereby to cause a spark and ignite the charge of commingled compressed air and 50 hydrocarbon received in the explosion chamber C.

When starting the system, it is, of course, obvious that the main shaft A cannot be turned by hand to revolve the piston in the 55 compressor to compress the air and hydrocarbon and force it into the explosion chamber since the motors are not in operation. Therefore, I provide a pipe 105 extending from the storage tank 89 to the explosive chamber C, 60 at the upper end of which pipe is located a valve 106, to the stem 107 of which an arm 108 is secured, the free end of the arm being connected by means of a link 109 to one arm of a bell-crank lever 110 pivoted to a post 65 111 secured to the upper side of the chamber

D. This bell crank lever is operated by a rod 112, secured to its free arm. When the pull and push rod 112 is operated in either direction, it causes the link 109 to open the valve 106 to permit the escape of an explosive charge to the explosive chamber C, and to close the valve. As soon as a sufficient charge has been admitted, the operator will push a button which will actuate a separate circuit, the wires of which are designated by 70 the numeral 113 to cause a spark between the sparking plug members 115 to explode the charge. As soon as the engine is in full operation, the method heretofore described involving the use of eccentric 95, rod 75 80 98 and spring-pressed head 103 may be resorted to. The explosion thus caused drives the burned gases out through the pipe 109 connected to the combustion chamber and to the motor respectively, thus providing the 85 motive power which operates the pistons in the motors.

The purpose of the three way valve 73 is to convey the charges to one side or the other of the compressor B, the piston of which is 90 driven by the main or line shaft A and the shaft in turn being driven by the motor, not shown. Thus when the direction of rotation of the shaft A is reversed, the direction of rotation of the piston in the compressor 95 is reversed as well, for which reason the compressor is provided with two inlet ports and two outlet ports, and the valves 73 and 81 are simultaneously reversed by means of the universal lever 69.

The air tight chamber D, may be filled with oil or other cooling medium if desired and receptacles 114 filled with sulfuric acid or other suitable cooling means may be disposed about the interior of the chamber to 100 aid in cooling the latter and prevent an excessive temperature therein.

It will be seen that many changes and alterations might be made in the form and arrangement of the parts described without 110 departing from the spirit and scope of my invention and hence I do not wish to limit myself to the exact construction herein set forth.

Having thus fully described my device, what I claim as new and desire to secure by 115 Letters Patent, is:—

1. In an explosive engine, the combination with a combustion chamber, of a pair of stationary electrodes therein, a source of compressed explosive material, a reciprocating arm received through the chamber, a main shaft adapted to reciprocate the arm, and a pin received in the arm for making mechanical and electrical contact with the electrodes.

2. In an explosive engine, the combination 125 with a combustion chamber provided with a plurality of stationary electrodes spaced apart from each other, of an arm passing loosely through the wall of the combustion chamber, a main line shaft, an eccentric 130

mounted thereon, an eccentric strap surrounding the eccentric, the outer end of the arm pivotally connected to the eccentric strap, a headed pin loosely connected to the inner end of the arm and having a slight movement with respect thereto, the pin adapted to be forced and temporarily held between the electrodes.

3. In an explosive engine, the combination 10 with a combustion chamber, and stationary electrodes mounted in the combustion chamber, of an arm passing through the wall of the chamber, a main line shaft, an eccentric

on the shaft, said eccentric secured to the arm, and a headed pin adapted to be received 15 in the arm, said headed pin adapted to be thrown in contact with the stationary electrodes.

In testimony whereof, I have signed this specification in the presence of two subscribing witnesses.

HUGH T. DUNN.
